UNITED STATES PATENT OFFICE.

LOUIS V. ARONSON, OF NEWARK, NEW JERSEY, ASSIGNOR TO VOICES INCORPORATED,
A CORPORATION OF DELAWARE.

SOUND DEVICE.

Application filed March 31, 1924, Serial No. 703,037, and in Canada March 21, 1924.

My invention relates to improvements in sound devices and is particularly adapted for use in toys such as dolls to provide means therein to cause them to utter sounds like ma-ma, etc. The main object of the invention is to provide a device of this class which is not only efficient in operation but which is also simple and unlikely to get out of order as well as being inexpensive and very compact. Further and more specific objects, features and advantages will more clearly appear from the detail description given below taken in connection with the accompanying sheet of drawings which form a part of this specification. In the drawings Fig. 1 is a vertical section through a device embodying my improvements in a preferred form thereof. Fig. 2 is a similar section taken at right angles to Fig. 1. Fig. 3 is a transverse section taken on the line 3—3 of Fig. 1.

Referring to the drawings, 1 represents a cylindrical container or casing preferably made out of heavy cardboard or the like and closed at the lower end by means of a sheet metal cap 2 crimped as at 3 to extend over the lower edge of the cylinder 1 and form an upwardly extending circular flange 4 fitting tightly around the outside of the lower end of the cylinder 1. 5 represents a flexible tubular bellows member preferably made of rubberized cloth. The lower end of this tubular bellows member 5 is rigidly secured to the lower end of the casing by reason of the fact that it extends between the crimped portion 3 and flange 4 of the head 2 and the end of the cylinder 1 so as to be tightly held therebetween. Secured to the upper end of the tubular bellows member 5 is a weighty head comprising a metallic dish shaped member 6 preferably composed of iron, steel or equivalent metal. The upper end of the tubular member 5 extends within the downwardly extending peripheral flange 7 of the member 6 and is firmly held therein and bound tightly against the inside surface of the flange by means of a circular clamping ring 8 inserted therein and fitting so tightly therein as to be held firmly therein by friction and the spring action of the ring.

The member 6 is provided with a centrally disposed rectangular aperture therethrough at 9 and in this aperture there is firmly cast a block of lead 10 also rectangular in transverse section. The block of lead 10 extends for a considerable distance above the top face 11 of the member 6 and also for a considerable distance below the bottom face of the member 6. The block of lead 10 is provided with a vertical aperture or slot at 13. The member 6 is also provided with an aperture therethrough at one side of the block 10 and in this aperture is fixed a reed pipe 14 provided with a sound reed 15. The reed pipe 14 may be sealed in the aperture through the member 6 by means of suitable wax or other sealing compound so as to be suitably held therein and any air forced out of the bellows will be caused to pass through the reed pipe. On the upper face of the member 6 there is provided a sound chamber 16. This chamber is made by providing a stamped out sheet metal inverted dish shaped member 17 and placing the same on top of the member 6 with its flange extending downwardly to engage the upper face of the member 6 as shown. The lower edges of the flange of member 17 may be secured and sealed to the member 6 by means of wax or other suitable sealing compound. The upper portion of the lead block 10 extends through the member 17 dividing the space therebeneath substantially in half, whereby a sound chamber 16 is formed on one side thereof. On the other side of the lead block 10 the member 17 is cut away as at 18, so that on this side of the lead block 10 the space which would otherwise be closed to the outside is quite open to the outside. Extending through the slot 13 is a flat plate 19 of steel or other suitable metal. The lower end of the steel plate or post 19 is rounded as at 20 and this rounded end fits within a rounded depression 21 stamped in the cover member 2 so that this end of the post 19 is held in relatively fixed position with respect thereto and to the casing when the parts are assembled. The upper end of the post 19 is also similarly rounded at 23 and this rounded end fits snugly within a rounded depression 24 in a metallic cap

member 25 secured on the top end of the casing 1 so that also the upper end of the flat post 19 is held relatively fixed with respect to the cap 25 and casing 1 when the parts are assembled. The rounded concave portions 21 and 24 form sections of spherical surfaces of substantially the same radius as that of the rounded ends 20 and 25 respectively. This permits the plate or post 19 to be easily turned about its vertical axis to accommodate any position which the vertical slot 13 tends to take as the weighty head slides back and forth on the post 19 while preventing any lateral movement of either end of the post 19 with respect to the casing or container. The cap 25 is rigidly secured to the casing 1 by being crimped over the upper edge thereof as shown at 26. The cap 25 is provided with numerous apertures 27 therethrough whereby the space in the container directly beneath the cap is open to the outside atmosphere.

On one side of the lead block 10 it is provided with a lateral aperture 28 extending from the slot 13 to the sound chamber 16. On the other side and directly opposite the aperture 28 the lead block is cut away as at 29. The weighty head comprising the member 6, lead block 10, etc. is adapted to slide by gravity up and down the post 19 which acts as a guide therefor, when the device is turned to different positions. The post or plate 19 is provided with a relatively narrow aperture therethrough at 30 in the top portion thereof and another relatively longer aperture 31 therethrough below the aperture 30.

The reed pipe or sounding means preferably consists of a member 14 which is semi-circular in cross-section, open at its upper end and substantially closed at its lower end and over the upper or otherwise open face of the member 14 is placed the reed 15, the same being firmly clamped thereto by a sheet metal clamp 35 which passes over the reed 15 and down under the flanges 36 of the member 14 as indicated at 37. In this way the metallic clamp 35 extending over the edges of the reed securely holds the latter in position on the reed pipe member 14.

In operation, the device is turned upside down so that the weighty head will approach as near as possible the cap 25. This will bring the aperture 28 above the aperture 30 as viewed in Figs. 1 and 2. Then if the device be turned to the position shown in Figs. 1 and 2, the weighty head will drop by gravity, sliding along and being guided by the flat post 19 and being prevented from tilting thereby by reason of the long slot through the lead block 10. I find that the use of a lead surface for such guiding means is particularly advantageous since there seems to be little friction and the arrangement is more efficient in operation. As

the weighted head descends under the action of gravity with the parts in the position shown in Figs. 1 and 2, the bellows 5 will be compressed thereby forcing air through the reed pipe and into the sound chamber 16. At first very little air can escape in this manner because the sound chamber is substantially closed to the outside atmosphere by reason of the fact that the opening 28 is above the opening 30 and only a very small amount of air can escape through the small leakage opening 32 in the sound chamber. This is insufficient to cause the reed to speak, but permits the weighty head to slowly descend. When, however, the head descends to a point where the opening 28 registers with the opening 30, a rush of air will take place through the reed pipe causing it to speak and utter a sound in the sound chamber 16 which passes out through the openings 28 and 30 and thence through the cap 25 to the outside and is easily heard. When the weighty head descends further so that the openings 28 and 30 no longer register, the post 19 covers the opening 28 and thus prevents the rush of air therethrough from the bellows and so causes the reed to cease speaking and the sound to be interrupted. The weighty head then descends slowly without causing any sound until the opening 28 registers with the opening 31 when another rush of air takes place through the reed pipe and another similar sound of longer duration is caused to be uttered in the same manner. This sound may be finally interrupted when the opening 28 passes by the opening 31 or the weighty member reaches the limit of its downward travel. It will be seen from the above that the sound chamber is provided with a sound opening 28 formed on one side of the sound chamber and that the plate 19 acts as a flat valve sliding over said opening 28 to control the emission of sound therefrom. The device is then turned upside down whereupon the weighty member will by gravity slide back toward the cap or top 25 and when the opening 28 has passed the opening 30, the device may be again turned to assume the position shown in Figs. 1 and 2 and the operation repeated. It will thus appear that during a single movement of the weighty head, the sounding means is caused to utter two sounds, one following another and by suitable selection of the reed, etc., these sounds simulate the word mama or papa, as desired.

From the above it will be seen that the device is extremely simple and efficient in operation, is very compact and is composed of very few and inexpensive parts whereby the same may be efficiently and cheaply constructed. While I have described my improvements in great detail and in connection with a preferred embodiment thereof, I do not desire to be limited to such details

or form since many changes or modifications may be made and the invention embodied in widely different forms without departing from the spirit and scope thereof in its broader aspects. I, therefore, desire to cover all forms and features coming within the scope or language of any one or more of the appended claims.

What I claim as new and desire to secure by Letters Patent, is:

1. A sounding device having in combination a container, a tubular bellows member having one end secured with respect to the container, a weighty head connected to the other end of the bellows member, said head being adapted to move back and forth in the container by gravity to compress and distend the bellows member, a sound reed operated by the bellows, and means for interrupting the sounding of the reed during one movement of the head whereby the reed will utter a plurality of sounds during one movement of the head, said head comprising a metallic dish shaped member with the end of the tubular bellows member extending within the peripheral flange thereof, and a clamping ring located within said metallic dish shaped member and binding the end of the bellows member about the inside of said peripheral flange.
2. A sounding device having in combination a container, a tubular bellows member having one end secured with respect to the container, a weighty head connected to the other end of the bellows member, said head being adapted to move back and forth in the container by gravity to compress and distend the bellows member, a sound reed operated by the bellows, and means for interrupting the sounding of the reed during one movement of the head whereby the reed will utter a plurality of sounds during one movement of the head, said head comprising a metallic member to which the end of the bellows member is peripherally attached, and said head having an opening therethrough with a body of lead fixed in said opening, said body of lead having an opening therethrough and said interrupting means including a relatively fixed post extending through and having sliding engagement with said last mentioned opening.
3. A sounding device having in combination a container, a tubular bellows member having one end secured with respect to the container, a weighty head connected to the other end of the bellows member, said head being adapted to move back and forth in the container by gravity to compress and distend the bellows member, a sound reed operated by the bellows, and means for interrupting the sounding of the reed during one movement of the head whereby the reed will utter a plurality of sounds during one movement of the head.
4. A sounding device having in combination, a tubular container, sheet metal caps for the ends thereof, a reed pipe therein, a weighty head adapted to move back and forth in the container by gravity, and to force air through the reed pipe to cause the reed thereof to speak when the head moves in one direction, a relatively flat plate having a plurality of apertures extending laterally therethrough, said plate extending through said head and acting as a guide therefor, the ends of said plate being rounded off and said caps having rounded depressions fitting said rounded ends for holding the plate in fixed relation in the container when the parts are assembled, and means cooperating with the apertures in said plate for emitting the sound from the reed pipe during the movement of the head which causes the reed pipe to speak.
5. A sounding device having a compression chamber and a weighty head movable by gravity to expel air from said chamber, said head comprising a metallic plate, a body of lead secured to said plate, and projecting therefrom, and a sound chamber adjacent the projecting portion, said projecting portion having an opening leading into the sound chamber, a reed pipe adapted to emit sound into the sound chamber when the air in said chamber is compressed, and a post extending through said body of lead and cooperating with the opening in said projecting portion to control the emission of sound therethrough.
6. A sounding device comprising a bellows with a weighty iron head movable by gravity to expel air from the bellows, said head having an aperture therethrough and a body of lead cast to the head at said aperture, a guide post extending through said aperture and through an aperture in said body of lead whereby the head is slidably arranged on said post, and sounding means operatively associated with said bellows.
7. A sounding device having a collapsible

air chamber with a weighty head movable by gravity to collapse said chamber, a guide member for the weighty head and along which the weighty head is adapted to slide, 5 said guide member extending through the weighty head, said weighty head having surfaces of lead where it engages the guide

member whereby the weighty head slides easily on the guide member, and sounding means operated by the movement of said 10 weighty head.

In testimony whereof I have signed my name to this specification.

LOUIS V. ARONSON.
